DESIGN FOR AN AMUSEMENT DEVICE

William J. Wendler, North Tonawanda, N. Y., assignor to Allan Herschell Company, Incorporated, Tonawanda, N. Y.

Application October 5, 1938, Serial No. 80,281

Term of patent 3½ years

To all whom it may concern:

Be it known that I, William J. Wendler, a citizen of the United States, residing at North Tonawanda, in the county of Niagara and State of New York, have invented a new, original, and ornamental Design for an Amusement Device, of which the following is a specification, reference being had to the accompanying drawings forming part thereof.

Fig. 1 is a perspective view of an amusement device, showing my new design;

Fig. 2 is a side elevation of the amusement device; and

Fig. 3 is a top plan view of the amusement device.

I claim:

The ornamental design for an amusement device, as shown.

WILLIAM J. WENDLER.
